UNITED STATES PATENT OFFICE

147,086

DESIGN FOR A FROZEN FOOD
DISPLAY CABINET

Daniel Robertson, Brantford, Ontario, Canada,
assignor to Universal Cooler Company of Canada, Ltd., Brantford, Ontario, Canada, a corporation of Canada

Application June 30, 1945, Serial No. 120,442

Term of patent 14 years

(Cl. D80—11)

To all whom it may concern:

Be it known that I, Daniel Robertson, a citizen of Canada, residing at Brantford, Ontario, Canada, have invented a new, original, and ornamental Design for a Frozen Food Display Cabinet, of which the following is a specification, reference being had to the accompanying drawings, forming part thereof.

Fig. 1 is a perspective view of a frozen food display cabinet showing my new design as it appears with the top cover thereof in open position. The opposite end of the cabinet is the same as shown except that there is no grate in the center of the opposite end panel. The rear portion is plain.

Fig. 2 is a front perspective view thereof but showing the device as it appears with the top cover in closed position.

I claim:

The ornamental design for a frozen food display cabinet, as shown and described.

DANIEL ROBERTSON.
